UNITED STATES PATENT OFFICE.

JOHN M. YOUNG, OF SAN FRANCISCO, CALIFORNIA.

CAN-END CLOSURE.

1,100,005.

Specification of Letters Patent. Patented June 16, 1914.

Application filed October 17, 1912. Serial No. 726,354.

To all whom it may concern:

Be it known that I, JOHN M. YOUNG, a citizen of the United States, residing in the city and county of San Francisco and State of California, have invented certain new and useful Improvements in Can-End Closures, of which the following is a specification.

The hereinafter described invention relates to the lining of what is known to the trade as "sanitary or double seaming can ends," that is, such ends the seaming flange of which are lined with some form of a packing in order that when the ends are applied to the can body by a double seaming, a tight joint or hermetical seal is formed without the use of solder.

The object of the invention is to make it practical to use a fibrous liner, preferably paper, and apply the same to the flange of the can end before the end is united to the can body and to so secure the same in position relative to the flange of the can end as to remove the danger of the liner ring falling off and becoming detached from the flange of the can end while being handled before or during the time of applying the end to the can body, or while the end with the fibrous liner applied thereto is being shipped from the factory to the cannery or canning establishment where it is to be applied to the open end of the can after the same has been filled with the food product.

Heretofore fibrous liners or liner rings have been secured to the flange of the can end by pasting or gluing the same thereto just prior to the end being applied to the end of the can body for the double seaming thereof, but at best such is only an insecure method of securing the liners or liner rings to the flange of the can end, inasmuch as the handling thereof by the workmen or operators tends to damage, tear or injure the liner ring to such an extent as to cause an imperfect seal to be formed when the can end is double seamed onto the can body and thereby causes a leaky joint. For the formation of a perfect hermetically sealed joint it is essential that the liner or liner ring applied to the flange of the can end be not marred or fall off, else the closing machine for double seaming the flange of the can end to the can body will make an imperfectly closed joint for the can.

To comprehend the invention, reference should be had to the accompanying sheet of drawings, wherein—

Figure 1 is a side view of a can partly broken away with the end cover and ring liner applied thereto. Fig. 2 is a bottom plan view of a can end cover with the fibrous ring liner positioned relative to the flange of the can end. Fig. 3 is a cross sectional view of the can end cover with the fibrous ring liner united to the flange thereof, said view illustrating the edge of the flange of the end cover as curled inwardly to hold the ring liner in place.

In the drawings, the numeral 1 is used to designate any suitable form of a metallic can body, and 2 the end covers or can ends united thereto by the usual double seam joint. The can end covers are preferably formed with a depressed channel 3 and an upraised central portion 4, and an outwardly projecting flange 5 extended from the end in a plane above that of the central portion thereof, and to the under face of which flange is applied, in any suitable manner, a fibrous ring liner 6, preferably formed of paper. This ring liner 6 is held in place by inturning or curling the outer edge of the flange 5, as shown at 7, Fig. 3 of the drawings, so that the ring liner is held within an annular groove 8 in the under face of the can end against displacement during the rough handling and usage to which the ends are subjected in canning establishments.

In applying the can end or end covers to the ends of the can body, the open end of the said body is forced against the fibrous ring liner 6 and the flange of the can end then united to the end of the can body by the usual double seaming process, which rolls or folds the lined flange of the can end to the end of the can body, the paper or fibrous ring liner completely filling the joint between the metal and producing a hermetically sealed joint for the ends of the can.

By the employment of a fibrous or paper ring liner for the flange of the can end there is provided a yielding seat against which the end of the can is forced during the operation of applying the ends thereto, which ring liner readily rolls or folds during the process of double seaming the flange of the end to the end of the can body and by so doing completely fills the joint so formed,

and this without any danger of the ring liner breaking or cracking during the formation of the end joint, and when the joint is formed and the seal made, there is no 5 impure material to be acted on by the contents of the can.

The advantages of applying the fibrous or paper ring as above described, to the under face of the can end flange to fill the 10 joint union when the end is secured to the can body, are a better and more efficient joint union or closure joint is formed; the providing of a non-leaky joint; disposing 15 of the danger of the ring liner breaking away from the can end flange to which it is applied; the liner ring does not become displaced during the handling to which the ends are subjected; and finally it is applied at a less cost than the cement, plastic and 20 composite linings for the can end flange and materially reduces the expense incident to the end joint of the cans, while at the same time providing an absolute hermetically sealed sanitary joint. By thus uniting or 25 securing the ring liner in place by curling or inturning the end of the flange of the can end, the ends may be lined at the can making factory and the lined ends shipped to the canning establishment in a condition for 30 double seaming to the can body, with the assurance that the ring liner or fibrous packing will not become loosened or marred during handling. This is a decided advantage 35 over the requirement that the ring liners be applied by hand as the end is about to be secured to the can body, for, as stated, such handling of the delicate fibrous ring liners

tends to injure the same and to cause the formation of an imperfect or leaky joint.

Having thus described the invention what 40 is claimed as new and desired to protect by Letters Patent is:—

1. A can end for the closure of sanitary cans having an outwardly projecting flange for the seaming thereof to the end of a can body, and a cut fibrous ring liner applied to the inner face of the can end flange and adapted to interfold with the said flange and the end of a can body during the seaming thereof to provide a sanitary packing for 45 the end joint of the can, said liner being held in position relative to the can end by inturning or curling the flange of the end to embrace or inclose a portion of said liner. 50

2. A can end provided with an outwardly projected circumferential flange, an integral fibrous ring liner secured to said end, said liner being held in place relative thereto by inturning the circumferential edge of the flange to partly embrace the liner ring. 55

3. The combination with a can end provided with a circumferential flange having its edge inturned to form an annular groove or channel, of a cut paper ring liner fitted onto said circumferential flange and held in 60 position relative thereto by the inturned edge of the said flange.

In testimony whereof I have signed my name to this specification in the presence of two subscribing witnesses.

JOHN M. YOUNG.
